Dec. 1259

Reuben H. N. Bates, of Providence, R. I.

Assignor to

J. Morrison, Jr. of Troy, N. Y.
Letters Patent No. 1259, dated June 19, 1860.

The schedule referred to in these Letters Patent and making part of the same:

To all whom it may concern,

Be it known that I, Reuben H. N. Bates, of the City and County of Providence, in the State of Rhode Island, have invented or produced a new and original design for Cooking Stove Plates, and I do hereby declare that the following is a full and exact description of the same, reference being had to the annexed Photographic drawings which make a part of this specification, and in which -

Fig: 1. is a side with doors; and

Fig: 2. a door, but on a larger scale than Fig: 1. -

The same letters refer to like ornaments on the different plates.

The side plate, A, has the ornament b, arranged along its top, and the ornament c, placed along just under the swell, d, along the after portion of the upper part of the plate, - all as fully shown in Fig: 1.

The plate B, or large door of the oven, has the running ornament f, between the mouldings g, and h, around its raised border; the ornaments i, i, in the two upper corners of the panel; and a center piece composed of the running ornament b, the mouldings j, k, check-work parts l, l, and cap-piece m, - all shaped and arranged together as is represented in Fig: 1.

The plate N, or door at the low part of the oven, and the door or panel O, at the end of the fire box, of the stove, each has the running ornament f, between the mouldings g, and h, around its raised border, and the ornament p, in each corner, & the oval piece composed of the check-work center q, and radiating border r; at the middle, of the plain panel; - the whole being shaped and disposed together in the manner represented in the annexed photographs: Fig: 1.

The door or plate S, has the vine-like ornament t, between the mouldings around its raised border; - the ornaments u, in the four corners, and the ornaments v, in the middle of the sides, of the outer panel; and the border moulding, the corner ornaments w, and the raised oval center piece bearing the ornaments x, x, and y, and surrounded by the ring of separate ornaments z; - all formed and arranged as shown in Fig: 2, of the annexed photographs.

What I claim as new, and of my invention or production and desire to secure by Letters Patent, is the ornamental design of the plates A, E, N, and S, of a Cooking Stove, as herein specified and represented in the annexed photographs.

Witnesses,

Thos. J. Kanelius,

Austin F. Park.

Ruben H. N. Bates.
